D N° 803. G Smith and H Brown

assignors to Abbott & Lawrence.

Star design (Star Air Tight.)

Figure 1. Patented June 15, 1856.

Des. 803

G. Smith & C. Brown of Philadelphia, Pa.

Assignors to J. G. Abbott & Archibald Lawrence, of the same place.

Letters Patent No. 803, Dated June 17th 1856.

The schedule referred to in these Letters Patent, and making part of the same.

To all whom it may concern:

Be it known that we, Garrison Smith

Des. 803

and Henry Brown, of the City and County of Philadelphia, and State of Pennsylvania, have produced a new and original Stove Design, designated as the "Star air tight". And we do hereby declare that the following is a full, clear and exact description of the same; reference being had to the annexed drawing forming part of this specification in which,

Figure 1, is a view of top plate

Figure 2, is a view of base plate

Figure 3, is a section of top plate showing elevated centre.

The edge of top plate A, has a moulding a, made up as shown in figure 3. The plate rises towards the centre, which has an opening B. Around this opening is a series of oval projections b, upon a wavy ground c, which terminates in foliage d. In each of the corners is an ornament e. On the front edge of the plate is the inscription "Abbott & Lawrence, Philad^a.", in raised Capitals. The details of the formation and arrangement of the several ornaments and mouldings of this plate, are fully set forth in figures 1 and 3.

The base plate C, is of the form shown in fig. 2, and bears on its surface the inscription "Star air-tight improved patented 1856", in raised capitals and numerals. The edge of the plate is ornamented with the undulating surface m, and projections n, and p, arranged and configured as shown in the drawing. The ash pit cover D, has a movable centre piece f, ornamented with figures q, and on each side of this centre piece bears foliage h, in bas-relief; the arrangement being as shown in figure 2.

We claim the design, configuration and arrangement of the several ornaments in bas-relief, and mouldings of the plates A, and C, as herein set forth, and represented in the drawing.

In testimony whereof, we have hereunto signed our names before two subscribing witnesses.
